US00D821595S

(12) **United States Design Patent** (10) Patent No.: **US D821,595 S**
Ito et al. (45) Date of Patent: **** Jun. 26, 2018**

(54) **NERVE STIMULATOR**

(71) Applicant: **OMRON HEALTHCARE Co., Ltd.**,
Muko-shi Kyoto (JP)

(72) Inventors: **Tamaki Ito**, Muko (JP); **Tsuyoshi Ogihara**, Muko (JP); **Takashi Shigeno**, Tokyo (JP); **Kazuya Andachi**, Tokyo (JP)

(73) Assignee: **OMRON HEALTHCARE Co., Ltd.**,
(JP)

(**) Term: **15 Years**

(21) Appl. No.: **29/596,905**

(22) Filed: **Mar. 13, 2017**

(30) **Foreign Application Priority Data**

Nov. 28, 2016 (JP) 2016-025736

(51) **LOC (11) Cl.** **28-03**

(52) **U.S. Cl.**

USPC **D24/200**

CLAIM

The ornamental design for a nerve stimulator, as shown and described.

DESCRIPTION

FIG. 1 is a perspective view of a nerve stimulator showing our new design;

FIG. 2 is a front view thereof;

FIG. 3 is a rear view thereof;

FIG. 4 is a top view thereof;

FIG. 5 is a bottom view thereof;

FIG. 6 is a right side view thereof; and,

FIG. 7 is a left side view thereof.

1 Claim, 7 Drawing Sheets
